ATTORNEY

UNITED STATES PATENT OFFICE.

GEORGE H. PLEASANCE, OF CLEVELAND, OHIO.

ELEVATOR.

SPECIFICATION forming part of Letters Patent No. 224,723, dated February 17, 1880.

Application filed December 31, 1879.

To all whom it may concern:

Be it known that I, GEORGE H. PLEASANCE, of Cleveland, in the county of Cuyahoga and State of Ohio, have invented certain new and useful Improvements in Elevators; and I do hereby declare the following to be a full, clear, and exact description of the invention, such as will enable others skilled in the art to which it pertains to make and use it, reference being had to the accompanying drawings, which form part of this specification.

My invention relates to elevators; and it consists in the combination, with a portable elevator-frame and an endless belt mounted on suitable rollers journaled in the opposite ends of the frame, of a steam-engine permanently attached to the elevator-frame and adapted to impart a continuous movement to the endless belt.

20 In the drawing, the figure represents one form or embodiment of my invention, wherein is shown, in side elevation, a frame supporting both an elevator-belt and a steam-engine cylinder, with suitable connections, whereby 25 the steam-engine can operate the elevator. There is also shown in this figure of drawing a portable steam-boiler and a flexible steam-pipe connection between said boiler and the engine upon the elevator-frame. My device is 30 here represented as in operation lifting barrels from a wagon to the second story of a house.

A is a frame, made of any suitable shape, dimensions, or material. As to whether said frame shall be all of a single section, or 35 whether it shall consist of two or more sections, someway connected or united, I care not; neither do I care whether it be constructed for operating one kind of an elevator-belt, B, or another, as said elevator-belt and apparatus 40 must be of a character and construction suitable to the use to which the device is designed to be put.

C is a steam-engine cylinder, of any sort or construction, and with it are associated the 45 valves and necessary apparatus to constitute a complete steam-engine.

D D are rollers or pulleys, over which the endless elevator-belt B is stretched. To one or both these pulleys or rollers D is connected 50 suitable gear or belt connection with the steam-engine C, so that said engine shall operate to revolve said pulley and thus move the elevator-belt B.

E is a flexible steam-pipe, and F is a portable steam-boiler.

It will be readily seen that my device is not only completely portable, but applicable to a wide range of uses, for the elevator-frame can be interposed between any load or collection of matter and the place where said matter is to be deposited, and steam-connection made by the flexible pipe E with the engine C; and now, when the steam-engine is set in motion, the elevating mechanism is ready to perform its function.

For loading and unloading cars and vessels, for lifting barrels, boxes, and merchandise, or for transferring it from one place to another, either on a level or up or down, my device is especially applicable. Its frame can be constructed to be used in any place where it is wanted, and power can conveniently be applied through the flexible steam-pipe, which, of course, can be of any required length.

I am aware that a metallic cable or band has been attached to the piston of a steam-engine, whereby a reciprocating motion equal to the stroke of the piston is imparted to the band or cable and the latter employed for hoisting or lifting articles, and hence I would have it understood that I make no claim to such construction and combination of parts, as my improvement relates to portable elevators having continuously-moving endless belts, the latter being actuated by a steam-engine permanently secured to the frame of the elevator.

What I claim is—

The combination, with a portable elevator having an endless belt mounted on suitable rollers journaled in said frame, of a steam-engine permanently secured to the elevator-frame, and intervening gearing connecting the steam-engine with one of the rollers of the elevator, whereby a continuous movement may be imparted to the endless belt by the power of steam, substantially as set forth.

In testimony whereof I have signed my name to this specification in the presence of two subscribing witnesses.

GEORGE H. PLEASANCE.
